METHOD OF PRODUCING AND MAINTAIN-
ING A VACUUM ON A CHAMBERFrederick L. Shelor, Richmond, Va., assignor to
Innovation Brakes, Inc., Richmond, Va., a
corporation of Virginia

Application March 7, 1932, Serial No. 597,359

2 Claims. (Cl. 188—152)

The invention relates to new and useful improvements in the method of producing and maintaining a vacuum on a chamber.

An object of the invention is to provide a method of creating a vacuum on a chamber of any desired ratio relative to a vacuum creating means operating thereon within the limits of said vacuum creating means, and for maintaining substantially constant the degree of vacuum on the chamber at the selected ratio.

In the drawing—

Figure 1 is a diagrammatic view showing one form of apparatus for carrying out the method;

Fig. 2 is a vertical sectional view through the control valve for determining the degree of vacuum placed on the chamber and for maintaining the vacuum at the selected degree or ratio relative to the vacuum creating means, the valve being closed, and

Fig. 3 is a view similar to Fig. 2, showing the valve shifted to an open position.

The invention has to do with a method of creating a vacuum on a chamber, which chamber is to be used in any desired way, such for example, as the applying of brakes to a rotating part, in which case one wall of the chamber will be made shiftable so that the difference in pressure between that on the chamber and atmospheric pressure may be utilized for forcing the braking member into contact with the rotating part. The chamber on which the vacuum is produced may be used as a supply chamber for maintaining a predetermined vacuum at various points in an apparatus of any type.

It is thought the method will be better understood by the description of the present illustrated embodiment of an apparatus for carrying out said method. In the drawing, a portion of a chamber is diagrammatically illustrated at 1 and this is the chamber on which it is desired to maintain a vacuum of a predetermined degree. A chamber is diagrammatically indicated at 2 which may be the chamber of the pump of a vacuum creating means, or a chamber associated with the pump on which a vacuum is created of substantially a predetermined degree, but by a greater degree than that which it is desired to maintain on the chamber 1. Interposed between the two chambers 1 and 2 is a control valve which includes a casing 3 having a pipe 4 leading from the casing to the chamber 1 and a pipe 5 leading from the casing to the chamber 2. There is a pipe 6 leading from the casing to a muffler 7. Within the casing 3 is a sleeve 8. This sleeve 8 is provided with a port 9 and with a tapering recess vanishing at

a point, and substantially V-shaped in cross section, indicated at 10. There is also a port 11 and a similar recess 12 leading from one wall thereof. The sleeve is likewise provided with a port 13.

This sleeve 8, as shown in the drawing, is connected to a lever 14 pivoted at 15 to a bracket 16 and pivotally connected at 17 to an arm 18 attached to the sleeve. The lower end of the lever 14 carries a clamping screw 19 shiftable in a slot 20 in a bracket arm 21. This provides a means whereby the lever 14 may be shifted to different set positions and secured in a set position.

Within the sleeve 8 is a cylindrical member 22 provided with a central chamber 23. There is a port 24 leading outwardly from this chamber which cooperates with the port 9, and a port 25 which cooperates with the port 11. There is likewise a port 26 cooperating with the port 13. When the ports are in the position shown in Fig. 2, the ports 13 and 26 are in alinement, and therefore, the chamber 23 in the member 22 is connected to the pipe 6 leading to the muffler 7. At this time there is a port 27 in alinement with a port 28, both of which are in alinement with the pipe 4, and thus the chamber 1 is connected through these ports with the chamber 23 and to the atmosphere. This provides a means whereby the control valve when in the position shown in Fig. 2, is closed to the vacuum creating means and the chamber 1 is fully opened and vented to the atmosphere. Such a condition is desirable when the method of creating a vacuum is applied to the control of a braking member for a rotating part.

The cylindrical member 22 carries an arm 29 through which a pin 30 passes. When the sleeve is shifted, the end of the sleeve engages the pin 30 and will shift the cylindrical member 22 with the sleeve. This cylindrical member is frictionally held in a set position by means of a friction clamping collar 31. The member 22 extends beyond the right-hand end of the sleeve and is provided with a flanged member 32 which has a tapered opening therethrough. A metering pin 33 with a similar taper extends into this opening. This metering pin is carried by a lever 34 pivoted at 35. The lever has a forked end straddling a pin 36 carried by the metering pin 33. A spring 37 is located between the inner side of the lever 34 and a shoulder on the metering pin and this provides a means whereby the spring yieldingly forces the metering pin against its seat in the member 32. Nuts 38 cause the lever when moved outwardly at its lower end to move the metering pin 33 away from the member 32, thus providing

an opening as shown in Fig. 3 of the drawing. The lever is controlled by a cam block 39 provided with a cam groove 40 in which a pin 41 carried by the lever moves. When the member 5 22 is moved from the left as viewed in Fig. 2, to the position shown in Fig. 3, then the lever is swung on its pivot so as to move the metering pin 33 outward relative to the seating member 32 and thus providing an opening to the atmosphere leading to the chamber 23.

When the valve is shifted to the position shown in Fig. 3, and is fixed in this position, the recess 10 is moved underneath the port with which the pipe 5 is connected and the chamber 23 is, therefore, in communication with the vacuum creating means or the chamber 2. It is, however, a throttled control, and not a wide open connection of the port 9. At this time, the recess 12 is also communicating with the pipe 4, and the 15 chamber 1 has a throttled connection with the chamber 23 of a character similar to the throttled connection between the chamber and the vacuum creating means. From certain aspects of the invention, the port leading to the chamber 25 1 may be wide open, but it is essential that the port leading to the vacuum creating means shall be throttled to the desired extent to produce a certain predetermined ratio of vacuum on the chamber 1. For example, referring to the degree 30 of vacuum on a chamber by the number of inches of mercury which it will sustain, the vacuum creating means may be of sufficient degree to sustain sixteen inches of mercury and with a proper setting of the valve and the metering pin, the 35 degree of vacuum on the chamber will be only sufficient to sustain four inches of mercury. In order that this vacuum on the chamber 1 may be maintained at four inches and not built up, the metering pin has been shifted so as to open or 40 vent the chamber 23 to the atmosphere. The shifting of the valve closes the port leading to the pipe 6, so that all connection to the atmosphere through the muffler has been cut off. With this setting of the valve, there is just sufficient 45 air admitted to the chamber 23 through the opening controlled by the metering pin 33 to maintain the vacuum pull on the chamber 1 constant, provided the pull of the vacuum creating means is constant. If there is a slight variation 50 in the vacuum pull of the vacuum creating means, then there will be a like change in the degree of vacuum developed on the chamber 1. In other words, the ratio of the vacuum on the chamber 1 to that on the chamber 2 will be 55 maintained constant for a given setting of the valve. The cam groove 40 is shaped so as to proportion the venting of the chamber 23 to the vacuum pull of the vacuum creating means for accomplishing the results stated. The block 39 60 may be shifted so as to vary the timing of the shifting of the metering pin 33 relative to the opening of the control port leading to the vacuum creating apparatus. The pipe 4 may lead to several chambers with which it is desired to 65 maintain a vacuum of substantially a predetermined degree. These chambers may be connected to various types of devices on which it is desired to create a vacuum, and the apparatus can be readily adjusted to the system to which it 70 is to be applied so as to maintain on said chamber 1 a substantially constant vacuum, varying only to the extent of the variation of the degree of vacuum developed by the vacuum creating means. Furthermore, the vacuum on the chamber 75 may be regulated at will by a shifting of the

valve. When it is desired to lower the degree of vacuum on the chamber 1 relative to that on the chamber 2, this can be accomplished by the shifting of the sleeve to the right, and thus closing partially the port leading to the vacuum creating means. The shifting of the valve does not shift the member 22 until the pin engages the end of the slot 42. The further shifting of the sleeve will, of course, shift the member 22 and partially close the metering pin. Thus it is that the chamber 1 may have the degree of vacuum thereon adjusted without opening the chamber to the atmosphere. This is particularly useful in the application of the method to the braking of a rotating part, as the wheels of an automobile, 15 as it permits the vacuum pull exerted on the brake chambers to be increased or decreased at will, without completely releasing the vacuum pull on the brake chambers.

From the above it will be apparent that I have 20 provided a method of creating a vacuum on a chamber which is of less degree than the vacuum creating means operating thereon, and of maintaining said vacuum on the chamber of lesser degree for any desired length of time. In order 25 to accomplish this, an intermediate control chamber is provided which is independently connected to the chamber on which the vacuum is to be drawn and the vacuum creating means. This chamber is also connected to the atmosphere and there are control valves so that the volume of air drawn from the control chamber for a given period of time may be decreased by the closing off of the valve between said chamber and the vacuum creating means. At the same 30 time, the volume of air drawn from the chamber on which the vacuum is to be created into the control chamber is similarly varied. The vent leading to the atmosphere is inversely varied, so that when the volume of air drawn from 35 the control chamber by the vacuum creating means is decreased, the volume of air from the atmosphere drawn into the chamber is increased, and thus by proportioning the amount of air drawn from the control chamber and fed to the 40 control chamber, a vacuum of a predetermined degree, less than that of the vacuum creating means can be obtained and maintained on this control chamber, and likewise on the larger chamber on which it is desired to create a vacuum. Then again, when the volume of air drawn 45 from the control chamber is increased for a given period of time by the opening of the passage leading to the vacuum creating means, the volume of air drawn in through the vent in the same 50 period of time will be decreased, and thus it is by controlling these ports leading to the atmosphere and leading to the vacuum creating means, any desired degree of vacuum within the limits 55 of the vacuum creating means may be selected and maintained.

In my co-pending application Serial No. 597,358, filed of even date herewith, and patented November 28, 1933, No. 1,937,444, the apparatus described in detail is shown, described 60 and claimed as applied to the braking of a rotating element, and no claim to this apparatus is made in this application. It will be understood that the method described and claimed 65 may be carried out by mechanisms of entirely 70 different construction from that shown and described.

Having thus described the invention, what I claim as new and desire to secure by Letters Patent, is—

1. The method of creating and maintaining a vacuum on a chamber of less degree than the vacuum creating means operating thereon, consisting in connecting said chamber and said vacuum creating means to a control chamber, varying the volume of air drawn from said control chamber in a given period of time, venting said control chamber to the atmosphere and inversely varying the amount of air drawn from the atmosphere into said control chamber in the same period whereby the degree of vacuum created on said control chamber may be changed to a predetermined desired degree within the limits of the vacuum creating means and maintained.
- 5 2. The method of creating and maintaining a vacuum on a chamber of less degree than the vacuum creating means operating thereon, consisting in independently connecting said chamber and said vacuum creating means to a control chamber, coordinately controlling the passages leading, respectively, to the vacuum creating means and the chamber on which the vacuum is to be created, venting said control chamber to the atmosphere and inversely controlling the opening of the passage leading to the atmosphere during the closing of the passages leading to the vacuum creating means and the chamber on which the vacuum is to be created.
